BUFFER

Filed May 14, 1929

UNITED STATES PATENT OFFICE

HARVEY W. BAILEY, OF PORTLAND, OREGON

BUFFER

Application filed May 14, 1929. Serial No. 363,051.

This invention relates generally to shock absorbing devices, and particularly to buffers.

The main object of this invention is to provide an exceedingly simple and efficient form of buffer employing a laterally supporting pneumatic member providing a resistance under load which increases as the pressure increases by reason of the confined pressure of the pneumatic element added to the natural resiliency of its structure, and further added to a frictional resistance with relation to a supporting member.

The second object is to provide a buffer which will be useful for a great variety of purposes, which will be noiseless in operation, and which makes it possible to utilize a form of pneumatic buffer which would be inherently unstable by providing a supporting guide for the tip of the buffer and a friction element for the sides of the buffer.

The third object is to provide a series of different mediums through which vibrations must pass for the purpose of intercepting the transmission of said vibrations.

These, and other objects, will become more apparent from the specification following as illustrated in the accompanying drawing, in which:

30 Figure 1 is a vertical section through a representative form of buffer.

Figure 2 is a transverse section taken along the line 2—2 in Figure 1.

35 Figure 3 is a perspective view of the buffer casing.

Figure 4 is a vertical section through a modified form of the buffer using an enlarged head supported by a buffer guide.

40 Figure 5 is a modified form of the buffer showing same unsupported by a guide but having its head metal covered.

Figure 6 is a section showing the use of the buffer illustrated in Figure 1 applied as a door stop.

45 Figure 7 illustrates the device shown in Figure 4 used as a glider under the front leg of a chair.

Figure 8 illustrates the device used as a glider for the back leg of a chair.

50 Figure 9 illustrates a further modifica-

tion of the device in which plurality of the cells are employed in series.

Similar numbers of reference refer to similar parts throughout the several views.

Referring in detail to the drawing, in Figure 1 there is illustrated a rubber buffer consisting of a somewhat cylindrical member having the tapering side walls 10 having a relatively heavy closed end 11 and a slightly enlarged open end 12 which forms a slight shoulder with a relation to the wall 10. The end 13 of the shoulder 12 is provided with a tapering inturned portion 14 which is quite flexible and provides the desired seal with relation to a confining part. The opening 15 is also preferably tapering, as is the thickness of the walls 10—that is to say, it is desirable to have the walls 10 expand gradually under a pressure exerted against the end 11 beginning with that portion of the wall 10 which is nearest the shoulder 12 and gradually working toward the end 11.

The device thus far described is made of rubber and is fitted into a buffer casing consisting of a cylindrical wall 16 having an out-turned flange 17 at one end thereof beyond which the end 11 normally projects.

It will be noted that the outermost portion of the walls 10 do not engage the interior of the casing 16, except near the end 12. However, when the entire buffer, as illustrated in Figure 6, is mounted in a door casing 18 and a door 19 is closed against same (as shown) then the end 11 is forced into the casing 16 causing an increase in pressure within the opening 15, and also a compression of the material in the walls 10, changing the shape thereof (as shown in Figure 6) which builds up a resistance comprised of an internal air pressure, the resiliency of the rubber itself and the friction between the rubber and the interior of the casing 16, thereby providing an exceedingly gentle but extremely efficient means of absorbing shock caused by the closing of a door or similar object.

In Figure 4 the buffer is shown equipped with a glider head 20 of relatively large area whose cylindrical portion 21 fits slidably within the casing 16 and receives the cylindrical end 22 of the buffer walls 10. This

- type of the device is especially designed as a glider for furniture, but if used on certain types of chairs which are subject to tipping backwardly it would preferably be used only on the front legs 23 (as shown in Figure 7) and if used on the back legs 24 a glider 25 of smaller diameter especially employed to prevent a canting or binding action with relation to the casing 16 should be used.
- 10 In the form shown in Figure 9 the shape of the buffer is modified still more. In this case it consists of a cup formed by the curved walls 26 having the inturned sealing lip 27 preferably rendered more flexible by forming an annular groove 28 around same. The cup 26 is mounted on a pedestal 29 as a base 30 which is secured to a base plate 31 in any convenient manner. The entire unit is placed within a casing 32 preferably having a smooth interior, and if much movement is required a number of these cups or cells are placed in series either with the cup ends adjacent to each other or with the base plate 31 of one unit engaging the cup end of the next unit.
- 15 25 With this form of the device there is secured the advantage of the compression of the air within the space 33 within the cup 26, and also within the space 34 outside of the cup 26.
- It is desirable to lubricate such devices with graphite or similar material since it can be seen that the frictional contact between the outer portion 35 of the cup 26 with relation to the casing 32 increases with the load applied thereto.
- 20 35 It can be seen that by this arrangement it is only necessary to vary the number and shape of the cells or units to secure the desired action whether it be short and strong or long and resilient, as the case may be.
- 40 45 This structure has the additional advantage of constantly keeping the rubber elements in compression and protected in a large measure against oxidation.
- The number of uses for which same can be employed is almost unlimited and ranges from typewriter mountings to shock absorbing devices of great magnitude.
- 50 I am aware that many forms of shock absorbing devices have been constructed in the past; it is therefore not my desire to protect such devices broadly, but I do intend to cover all such forms and modifications thereof as fall fairly within the appended claims.
- 55 60 Claim:
1. A buffer consisting of a tapering elongated rubber cell whose resiliency increases toward its smaller end, a head on its smaller end to which pressure can be applied, said head serving as a guide for directing said pressure along the axis of said buffer, and a buffer casing for supporting the walls of said cell against outward expansion and for the purpose of adding a frictional resistance to the compressive and resilient resistance of said cell.
2. A buffer consisting of a casing, a metal base slidably mounted in said casing, a flexible cup mounted on said base within said casing, and flexible means for sealing the open end of said flexible cup under pressure.
3. A buffer consisting in combination of a cylindrical casing and a plurality of pneumatic cells mounted within said casing each of said cells having a guiding base formed thereon slidably mounted within said casing the outer portion of each cell normally not contacting with said casing but expanding under load to engage said casing with increasing pressure as said load increases and to offer increased resistance to said load as each cell in succession expands its diameter and increases its air pressure within and without its cell.
